UNITED STATES PATENT OFFICE.

GEORGE R. DE NISE, OF DENVER, COLORADO.

STRETCHING ATTACHMENT FOR OPERATING-TABLES.

No. 902,947.

Specification of Letters Patent.

Patented Nov. 3, 1908.

Application filed July 3, 1907, Serial No. 382,092. Renewed August 28, 1908. Serial No. 450,744.

To all whom it may concern:

Be it known that I, GEORGE R. DE NISE, citizen of the United States of America, residing at Denver, in the county of Denver and 5 State of Colorado, have invented certain new and useful Improvements in Stretching Attachments for Operating-Tables, of which the following is a specification.

This invention relates to attachments for 10 the class of operating tables employed by surgeons, physicians and osteopaths, in the treatment of various ailments and the performance of surgical operations, and its object is to provide means which may be readily applied to any one of the many operating 15 tables now in use, and which, when thus attached, will adapt the table to the purpose of producing a stretching action upon the body of a person reclining upon its upper surface, 20 with the object of strengthening the nervous system, and increasing the height of the user by restoring the natural elasticity to the abnormally hardened cartilaginous tissues in the human body, and strengthening the 25 muscles which by want of continual action, are weak and undeveloped.

I attain these objects by the mechanism illustrated in the accompanying drawings in the various views of which, like parts are 30 similarly designated and in which—

Figure 1—represents a side elevation of an operating table with my attachment in operative position, Fig. 2—a plan view thereof, Fig. 3—an enlarged side elevation of the 35 head-end member of the attachment—Fig. 4—a plan view thereof—Fig. 5—an enlarged side-elevation of the foot-end member of the attachment—Fig. 6—a plan view thereof, and Fig. 7—a perspective view of a bar or 40 brace used under certain circumstances, in connection with my attachment.

Referring to the drawings, let the reference numeral 2 designate an operating table, which, as stated in the preamble, may be of 45 any design or construction.

The stretching attachment comprises two elements 3 and 4, which in practice, are attached respectively to the head-end and the foot-end of the table.

50 The head-end element 3, consists of a support adapted to uphold and secure the upper portion of the human body and comprising a U shaped frame 5, including the parallel arms 6 and the transverse connection 7, 55 which being bent at right angles to the said

arms, provides means for the attachment of a head gear 8, the construction and application of which will hereinafter be described.

The free extremities of the arms 6, are bent downwardly at right angles thereto, and 60 their extreme ends 9, are turned at right angles to the downwardly ranging offsets, to extend in parallel relation to the main body of the frame.

To attach the frame to the operating table 65 I employ a bracket 10 designed to be secured to a convenient part of the table, by means of screws, rivets or bolts, and comprising a strap or body portion 10^a and two terminal, outwardly extending, apertured ears 10^c, 70 which, in practice, engage the inner surface of the correspondingly apertured extremities 9 of the frame, and are pivotally connected therewith by means of a bolt 11, inserted through the registering apertures and se- 75 cured by a nut 11^a.

The frame 5 is provided, in proximity to its outer extremity, with a transverse bar 12 to the underside of which is pivotally secured a brace 13, composed of two members 13^a 80 and 13^c, each provided with a plurality of equidistantly arranged, longitudinally aligned apertures 14, for the insertion of bolts 15, by means of which the two members are rigidly connected. 85

The outer member 13^c terminates in a saddle 13^d which is designed to straddle and engage a brace 16, such as is usually found on operating tables to connect the lower portions of their legs or supports. 90

Should it be desired to attach the device to a table constructed without the transverse braces 16, the required support for the extremity of the member 13^c of the brace 13 may be supplied by a separate bar 17 adapted to be secured to the lower portion of the operating table, and which in the capacity in which it is employed, may form part of the attachment. 95

By adjustment of the position of the short member 13^a of the brace in relation to its upper portion, the said brace may be lengthened or shortened to conform with tables of varying constructions or to regulate the angle of the support 5 in relation to the upper 100 surface of the table to which it is attached.

A continuous belt 18, composed of rubber, canvas, felt, leather or other flexible material, is stretched around the parallel arms of the 105 frame 5, to provide a support for the pa- 110

tient's head, when the latter during the stretching operation, is held in fixed relation to the frame by means of the hereinbefore mentioned head-gear 8. The latter, which 5 may be of any desired form or construction, is preferably composed of a cap 8^a, provided with two straps 8^c secured at their opposite ends and connected at the point of their intersection by a ring 8^d which in practice, is 10 attached to a hook 19, secured upon the transverse member 7 of the frame 5.

A third strap 8^c, surrounds the cap near its lower edge, and is arranged to press upon the brow and upon the occiput or posterior 15 part of the patient's calvarium, when the cap is in place.

Pivottally secured upon the arms 6 of the frame, in proximity to its offsets, are two stops 20, designed to relieve by engagement 20 with the axillæ of the patient, the head, neck and contiguous parts, of the greater 25 part of the tension produced by the stretching action to which he is subjected.

Each of the stops comprises an angularly 25 bent strap, pivottally secured at one of its extremities to the arms 6, while its opposite, upwardly ranging portion is provided with a cushion 20^a, preferably composed of doubled rubber tubing, to prevent injury to the parts 30 of the patient's body with which the stops come in contact.

The transverse connection 7, is furthermore provided with hooks or eyes 21 secured 35 near its extremities and intended to provide means for securing the patient's wrists, when to promote the development of the thoracic muscles and organs, the body is subjected to the stretching action with the arms extended above the head.

40 The foot element 4 of the attachment comprises a U shaped frame 22, including the parallel arms 22^a and the transverse connection 22^c which support the mechanical appliance through instrumentality of which the 45 body of the patient reclining upon the table is subjected to the stretching action. This appliance consists of a tackle 23, comprising a standing double block 24 and a running block 25, through which is rove a rope 26, 50 one extremity of which is fastened to a cleat 27 secured within the frame, while its opposite end or fall connects with a shaft 28 provided with a crank 28^a and rotatably mounted in apertures in the arms 22^a and in trans- 55 verse relation thereto.

A ratchet wheel 29 upon the shaft, in cooperation with a gravity pawl 30 upon the adjacent part of the frame 22, prevents retrograde motion of the shaft during the winding 60 process.

The standing block 24 is preferably connected with the outer extremity of the short arm 31^a of a bent lever 31 which is fulcrumed in a clevis 32, secured to the transverse 65 member 22^c of the frame, and whose oppo-

site long arm 33 connects at its extremity with an indicating appliance 34 by means of which the amount of tension to which the patient's body is subjected, may be determined.

The appliance 34 consists of an ordinary spring balance the housing 34^a of which connects with the lever, while the parts arranged to compress its spring and which are connected with the indicatory pointer 34^c, are 75 secured by means of a staple 35 to the adjacent arm 22^a of the frame.

The reference numeral 36 designates the appliance by which the feet of the person reclining upon the table 2, may be connected 80 with the tackle and which comprises two members 37, each composed of an ankle strap 37^a which, in practice, is fastened around the tarsus of the patient, and a flexible loop 37^c which passes around the sole of 85 the foot.

The loops 37^c of the two members are connected by a strap 38 which passes loosely through an eye 25^a on the running block 25 of the tackle.

The free ends of the arms 22^a of the frame 22 are apertured and may be pivottally attached to the table by means of a bolt 39 and two angle straps 40 designed to be secured upon the table by means of bolts, screws or 95 rivets and provided in one of their flanges with a plurality of longitudinally alined holes, adapted to admit the bolt 39.

To secure the element 4 upon the operating table, the angle straps 40 are secured against 100 its foot end in vertical parallel relation to each other and at equal distances from the center of the table. The apertured extremities of the arms 22^a of the frame 22 are now placed in engagement with the inner surface 105 of the outwardly extending, apertured flanges of the bar 40, and the parts secured together by the before mentioned bolt 39 which being inserted through their registering apertures, is held in place by a nut 39^a 110 screwed upon its threaded extremity.

The U-shaped frame 22 is furthermore provided with a brace 41 pivottally secured in central relation to the transverse member 22^c and comprising two adjustably connected 115 members 41^a and 41^c which in form, arrangement and application are identical to the parts 13^a and 13^c of the brace 13 at the head-end element of the attachment.

The saddle 41^d at the extremity of the 120 short member 41^c engages when in place, a horizontal brace 42 at the lower portion of the table, or a separate bar 17 may be employed to provide the required support as hereinbefore explained.

Having thus described the mechanical construction of my attachment, its operation in conjunction with an operating table will be readily understood.

The frames comprised in the two elements 130

being pivotally attached at opposite ends of the table in the manner described, are held in an approximate horizontal position so as to form extensions of the table's upper surface, by means of the longitudinally adjustable braces 13 and 41, and when not in use they may be lowered in substantial parallel relation to the ends of the table as shown in broken lines in Figs. 3 and 5 of the drawings, 10 by disengaging the saddle extremities of the said braces from the transverse support on the lower portion of the table.

When the elements are in their extended, operative position, the patient is placed in a 15 reclining posture upon the upper surface of the table, after which the cap 8 is adjusted upon his head and the ankle straps comprised in the foot-gear, are secured to his lower limbs. The operator now pulls the standing 20 part of the rope 26, which prior to the adjustment of the foot-gear had been unfastened from the cleat 27, until its running and fall portions are taut.

Having refastened the rope, he now places 25 the stops 20 in engagement with the arm-pits of the patient, and by manipulation of the crank 28^a winds the rope upon the shaft until the desired degree of tension is attained.

To release the tension, the end of the rope 30 may be unfastened from the cleat, the gravity dog lifted out of engagement with the ratchet wheel on shaft, or the head-gear may be detached from the transverse member 7 of the frame 5.

Having thus described my invention, what 35 I claim is:—

1. An attachment of the class named comprising two elements adapted to be pivotally secured at opposite ends of an operating table and respectively having means to hold an extremity of a body reclining upon the said table, in fixed relation thereto, and to produce a stretching action at its opposite extremity.

2. An attachment of the class named comprising two elements adapted to be pivotally secured at opposite ends of an operating table and to coöperatively produce a stretching action upon a body reclining thereon, and 50 means to adjustably hold the said members in the operative position.

3. An attachment of the class named comprising two elements adapted to coöperatively produce a stretching action upon an 55 interposed body, each of the said elements comprising a member adapted to be secured to an operating table, a frame pivotally connected therewith and means on the latter to adjustably hold it in operative position to the 60 said table.

4. An attachment of the class named comprising two elements adapted to be secured at opposite ends of an operating table, one of the said elements having means to 65 hold an extremity of a body reclining upon

the said table in fixed relation thereto and the other element having a gear adapted to connect with the opposite extremity of the said body, and a tackle appliance adapted to impart a stretching action to the said gear. 70

5. An attachment of the class named comprising two elements adapted to be secured at opposite ends of an operating table, one of the said elements having means to hold an extremity of a body reclining upon 75 the said table, in fixed relation thereto and the other element having a gear adapted to connect with the opposite extremity of the said body, and a tackle appliance adapted to impart a stretching action to the said gear by 80 manipulation of either end of the rope included therein.

6. An attachment of the class named comprising two elements adapted to be secured at opposite ends of an operating table, 85 one of the said elements having means to hold an extremity of a body reclining upon the said table, in fixed relation thereto and the other element including a frame, a winch thereon, a tackle appliance including a rope 90 operatively connected with the said winch, and a gear adapted to connect with the opposite extremity of the said body, attached to the said appliance.

7. An attachment of the class named 95 comprising two elements adapted to be secured at opposite ends of an operating table, one of the said elements having means to hold an extremity of a body reclining upon the said table, in fixed relation thereto and 100 the other element including a support, a standing block fixed thereon, a running block, a rope operatively connecting the said blocks, means on the running block to connect with the opposite extremity of the 105 said body, and a winch connecting with the rope.

8. An attachment of the class named comprising two elements adapted to be secured at opposite ends of an operating table, 110 one of the said elements having means to hold an extremity of a body reclining upon the said table, in fixed relation thereto and the other element including a tackle, a gear connected therewith and adapted to connect 115 with the opposite extremity of the said body, and indicator means connected with the tackle so as to indicate the amount of force excited upon the said gear through instrumentality of the tackle. 120

9. An attachment of the class named comprising two elements adapted to be secured at opposite ends of an operating table, one of the said elements having means to hold an extremity of a body reclining upon the said 125 table in fixed relation thereto and the other element including a frame, a lever fulcrumed thereon, a tackle connecting with one of its arms, a gear adapted to connect with the opposite extremity of the said body, connected 130

with the tackle, and means adapted to indicate the force exerted by the said tackle, connected with the opposite arm of the said lever.

5 10. An attachment of the class named comprising two elements adapted to be secured at opposite ends of an operating table, one of the said elements having means to hold an extremity of a body reclining upon 10 the said table in fixed relation thereto and the other element including a frame, a lever fulcrumed thereon, a tackle connecting with one of its arms, a gear adapted to connect with the opposite extremity of the said body, 15 connected with the tackle, and a spring balance connected with the frame and with the opposite arm of the said lever.

11. An attachment of the class named comprising two elements adapted to coöperatively produce a stretching action upon 20 an interposed body, means pivotally connected with one of the said elements to vertically adjustably secure it to an operating table, means pivotally connected with the 25 other element to secure it to the said table, and means to support the said elements adjustably in operative position.

12. An attachment of the class named comprising two elements adapted to be secured at opposite ends of an operating table, 30 means upon one of the said elements to produce a stretching action upon the lower extremity of a patient reclining upon the said table, a head gear upon the other element 35 adapted to secure the patient's head in fixed relation thereto, and stops pivotally secured upon the last named element to engage the patient's arm pits.

13. An attachment of the class named 40 comprising two elements adapted to be secured at opposite ends of an operating table, means upon one of the said elements to produce a stretching action upon the lower extremity of a patient reclining upon the said 45 table, a head gear upon the other element adapted to secure the patient's head in fixed relation thereto and stops pivotally secured upon the said element, adapted to engage the patient's arm pits and comprising bent arms 50 and cushions formed by doubled elastic tubing, secured to the upwardly ranging portions thereof.

14. An attachment of the class named, comprising two elements adapted to coöper-

atively produce a stretching action upon an 55 interposed body and each including a frame, means at one extremity thereof to pivotally secure it to an operating table and a longitudinally adjustable support, secured in proximity to its opposite end. 60

15. An attachment of the class named, comprising two elements adapted to coöperatively produce a stretching action upon an interposed body and each including a frame, means at one extremity thereof, to 65 pivotally secure it to an operating table and a support pivotally secured in proximity to its opposite end and composed of two detachably connected members, the lower one of which is adapted to connect with a cross 70 bar on the said table.

16. An attachment of the class named comprising two elements adapted to coöperatively produce a stretching action upon an interposed body and each including a 75 frame, means at one extremity thereof to pivotally secure it to an operating table and a longitudinally adjustable brace pivotally secured in proximity to its opposite end, and supporting members adapted to be secured 80 to the lower portion of the table and to connect with the lower extremity of each brace.

17. The combination with an operating table of two elements hingedly secured at one of their extremities at opposite ends thereof, 85 and adapted to coöperatively produce a stretching action upon a body reclining upon the table, and means to adjustably hold the said elements in their operative positions.

18. The combination with an operating 90 table of two elements hingedly secured at one of their extremities at opposite ends thereof, and means to adjustably hold the said elements in their operative positions, one of the said elements having means to 95 hold an extremity of a body reclining upon the said table in fixed relation thereto and the other element having a gear adapted to connect with the opposite extremity of the said body and a tackle appliance adapted to 100 impart a stretching action to the said gear.

In testimony whereof I have affixed my signature in presence of two witnesses.

GEORGE R. DE NISE.
